UNITED STATES PATENT OFFICE.

WILLIAM A. HEIDE, OF DETROIT, MICHIGAN.

SPARK PLUG.

Application filed July 8, 1920. Serial No. 393,800.

To all whom it may concern:

Be it known that I, WILLIAM A. HEIDE, a citizen of the United States, residing at Detroit, in the county of Wayne and State of Michigan, have invented a new and useful Spark Plug, of which the following is a specification.

This invention relates to spark plugs, one of its objects being to provide a device of this character the electrode of which is adapted to be placed in the path of the incoming gas and close to the gas inlet port where the velocity of the gas is greatest and will exert a blowing or cutting action through the spark gap, thereby to prevent the carbon from accumulating.

A further object is to provide a spark plug so constructed that the end of the electrode can be readily adjusted the required distance from the terminal or contact cooperating therewith even though the same is not visible.

A still further object is to provide an electrode cooperating with the engine block in such a manner that the spark will jump from the electrode to the wall of the block close to the gas inlet, as before stated.

With the foregoing and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred forms of the invention have been shown.

In said drawings—

Figure 1 is a section through a spark plug such as constitutes the present invention.

Figure 2 is a similar view showing a slightly modified form of spark plug.

Referring to the figures by characters of reference 1 designates a portion of the block of an engine having a gas intake port 2 and adjacent this port is arranged a screw plug 3 constituting one of the terminals of the spark gap. The other terminal consists of the electrode 4 of the spark plug constituting the present invention. This spark plug includes a shell 5 adapted to be screwed into the block 1 and provided with an interior shoulder 6. Supported on this

shoulder is an annular enlargement 7 formed upon a core 8 of porcelain or other insulating material, this core projecting close to the inner end of the shell 5 where it is recessed, as shown at 9 while the other end of the porcelain core is extended outwardly beyond the shell and is surrounded by a sleeve nut 10 which is screwed into the shell 5 and serves to hold the enlargement 7 upon the shoulder 6. Obviously any suitable packing material indicated generally at 11 can be interposed between the enlarged portion 7 and the shoulder 6 and nut 10.

Mounted on the upper end portion of the insulating core 8 is a sleeve 12 of fiber or other suitable insulating material, that portion of the sleeve surrounding the porcelain core being split, as indicated at 13 and surrounded by a clamp 14 which, when tightened by means of a bolt 15, will cause the insulating sleeve 12 to bind upon the core 8.

Suitably secured within the sleeve 12 is a bushing 16 interiorly screw threaded, this bushing being engaged by a screw plug 17 having a recess extending thereinto from its inner end as shown at 18. A lock nut 19 is mounted on the screw plug. The electrode 4 extends through the insulating core 8 and through the plug 17 and is engaged by nuts 20 located in the recess 18 and which bind together so as to be locked against rotation on the electrode. This electrode is slideable to a limited extent within the screw plug 17, its sliding movement being limited by a nut 21 which also cooperates with another nut 22 on the electrode for securing a terminal wire to the electrode.

In applying this spark plug to an engine the shell 5 is screwed into the block 1. The lock nut 19 is loosened and the plug 17 is screwed into the bushing 16 until the end of the electrode 4 comes into contact with the terminal 3. The nut 21 is then unscrewed so as to move away from the plug 17 a distance equal to the spark gap to be provided between the electrode 4 and the terminal 3. After this accurate adjustment of the nut 21 has been effected the electrode 4 is held pressed against the terminal 3 while the plug 17 is unscrewed from the bushing 16 until it comes against the nut 21. The lock nut 19 is then screwed down against the bushing 16 so as to hold the plug 17 against further movement after which the nut 21 is screwed onto the electrode so as to draw said electrode longitudinally until the nuts

20 come against the end of the plug 17. This obviously will shift the electrode a distance exactly equal to the desired spark gap. A wire terminal can then be placed on the 5 electrode between the nuts 21 and 22 and clamped by adjusting the nut 22 downwardly thereagainst.

Various modifications of the structure described can of course be made, as will be 10 obvious. For example, instead of providing the sleeve 12 with a clamp for holding it in place, a sleeve 23 can be extended between the insulating core 8 and the sleeve nut 24, one end of the sleeve 23 being out turned 15 so as to be held between the inner end of the sleeve nut 24 and the enlargement on the insulating core. This has been shown clearly in Figure 2.

What is claimed is:

- 20 1. In a spark plug the combination with a shell and an insulating core, of an electrode, and means for adjusting the electrode longitudinally relative to the core, said means including a threaded member through 25 which the electrode extends, means upon the electrode and within said member for holding the electrode against movement in one direction relative to the member, means upon the electrode for engaging the outer

portion of said member for indicating the 20 size of a spark gap to be produced, said member being shiftable against the gap indicating means to support the electrode at the proper point to produce the desired gap, 25 means for locking said member in shifted position relative to the insulating core, and means for securing the electrode to the member and against relative movement after it has been adjusted to a spark gap of the desired size.

2. A spark plug including a shell, an insulating core, a bushing connected to said core, a screw plug engaging the bushing, an electrode slidably mounted with the plug and core, means upon the electrode and within the plug for limiting the movement of the electrode in one direction relative to the plug, a combined gauge and lock nut upon the electrode for engaging the outer surface of the plug, and a lock nut upon the plug 50 for engaging the bushing.

In testimony that I claim the foregoing as my own, I have hereto affixed my signature in the presence of two witnesses.

WILLIAM A. HEIDE.

Witnesses:

DERRICK S. BROWN,
P. A. LOERSCH.
